UNITED STATES PATENT OFFICE.

ALFRED W. BRUCE, OF NEW YORK, N. Y.

LOCOMOTIVE BOILER.

Application filed February 7, 1927. Serial No. 166,391.

My invention relates to locomotive boilers of the general class or type in which the side walls of the fire box are formed of water tubes, instances of which are exemplified in 5 the patent of J. M. McClellon, No. 1,580,063, dated April 6, 1926, and in the patent to myself, No. 1,624,655, dated April 12, 1927.

My present invention is particularly directed to an improvement in the boiler of 10 my patent aforesaid, and comprises a simplification of the feed water connections between the firebox and the barrel sections of the boiler, an improved connection of the water tubes to be steam drum, the provision 15 of a back head adapted to support the drum with the capacity of relative movement, and the embodiment of a readily insertible and removable bridge wall at the forward end of the fire chamber.

20 The improvement claimed is hereinafter fully set forth.

In the accompanying drawings: Figure 1 is a vertical longitudinal central section through a locomotive boiler embodying my 25 invention; Fig. 2, a one-half horizontal, longitudinal section through the middle plane of the boiler; Fig. 3, a view, half in rear elevation, and half in vertical section on line III—III of Fig. 1; Figs. 4, 5 and 6, vertical 30 sections, on the lines IV—IV, V—V and VI—VI, respectively, of Fig. 1; Fig. 7, a vertical longitudinal central section through a locomotive boiler illustrating a structural modification of my invention; Fig. 8, a horizontal half section thereof; Figs. 9 and 10, vertical transverse sections, on the lines 35 IX—IX and X—X, respectively, of Fig. 7; and Fig. 11, a section on the line XI—XI of Fig. 10.

40 In the practice of my invention, referring descriptively to the specific embodiment thereof which is herein exemplified, the locomotive boiler comprises a fire box, A, and a boiler barrel, B, connected thereto, through 45 which barrel there extends a plurality of fire tubes, 1, in the ordinary manner. A combustion chamber, D, is formed in the forward portion of the fire box. A hollow mud ring, 3, is connected to the bottom ends of, 50 and supports, a plurality of water tubes, 10, which are set closely together and form the side walls of the fire box, A. The water tubes, 10, are preferably, as shown, staggered at the points of their connection to a steam drum, 11, which extends horizontally and 55 forwardly from the back head, 4, into the

barrel, B, said drum being supported in, and passing freely, by a slip joint, through the outer sheet, 6, of the back head of the fire box. The staggered disposition of the upper ends of the side water tubes, provides additional metal between the receiving apertures in the wall of the drum, and thereby affords a proper factor of safety for the drum, without necessitating additional reinforcing means.

60 The back head of the boiler comprises a plurality of water tubes, 4, extending upwardly across the back of the fire box, and an outer sheet, 6, of substantial thickness, the upper portion of which is riveted to a wrapper sheet, 15, and which is secured, at bottom, to the mud ring, 3. The water tubes, 4, are connected, at their bottom ends, to, and supported by, the transverse rear portion of the mud ring, and, extending upwardly, are secured, at their tops, to the wall of the drum, 11. A saddle shaped water cooled bridge wall, 9, is supported on the transverse forward portion of the mud ring, 80 said bridge wall extending across the fire box, and having water passages, 9^a, communicating with the mud ring, between the rivets by which it is secured thereto. The bridge wall is preferably secured only to the mud ring, so as to permit it to expand and contract freely, and the transverse forward portion of the mud ring is inclined upwardly 85 toward the longitudinal central plane of the fire box, so as to provide room for a suitable feed water connection, 17, of the barrel with the mud ring. Arch tubes, 12, which support a fire brick arch, 13, are secured to the bridge wall, through which they communicate with the front of the mud ring, and extend upwardly and rearwardly to the drum, 11.

90 The sides of the combustion chamber, D, are formed of water tubes, 10^a, which form continuous walls with the water tubes, 10, of the fire box, and conform, in curvature, with said tubes, above the horizontal middle plane of the boiler. The tubes, 10 and 10^a, are, at their tops, connected to the drum, 11, and, at their bottoms, to the mud ring, 3, and to the feed water connection, 17, leading from the barrel to the mud ring. This connection provides a passage for water from the barrel to the bottom ends of the water tubes, 10^a, and also supplies feed water 95 to the mud ring, and, through it, to the side water tubes, 10, of the fire box, the arch 100

tubes, and the water tubes of the back head.

5 A wrapper sheet, 15, which covers the top of the firebox, is connected to the barrel, B, and tube sheet, 2, said wrapper sheet performing the function of firmly connecting the fire box to the barrel of the boiler, and imparting strength and rigidity to the entire structure, and also of forming a housing or casing for the top of the fire box.

10 Suitable lagging or insulating material, 16, is provided between the outside of the water tubes, 10, 10^a, and the inside of the wrapper sheet, 15, and similar material is also applied between the back head tubes, 4, 15 and the outer sheet, 6. The forward end of the feed water connection, 17, is supported by the downward extension, 2^a, of the tube sheet, 2, which is secured to the barrel, and closes the rear end of the steam and water space thereof. Access to the feed water connection, 17, is obtained through a front man-hole, closed by a cover, 17^a.

25 My invention is of substantial advantage in providing a rigid boiler structure and a flexible fire chamber, as the tubes, 10, 10^a, 4 and, 12, and the drum, 11, are free to expand or contract within the rigid structure comprising the barrel, B, the throat sheet, 2, the wrapper sheet, 15, and the rear fire box sheet, 6. The drum, 11, is also free to 30 move longitudinally in expanding or contracting, as it has merely a snug and supporting fit in the rear sheet, 6.

35 Figs. 7 to 11 inclusive illustrate a structural modification, in which the ordinary water space back head, having inner and outer sheets, 5, and 6, connected by staybolts, 7, is applied. The bridge wall between the fire box and combustion chamber is also 40 different from that before described, in being formed of fire brick.

I claim as my invention and desire to secure by Letters Patent:

45 1. In a locomotive boiler, the combination of a barrel; a fire box, comprising a combustion chamber and a fire chamber; a back head, having a rigid outer sheet and closing the rear of the fire chamber; a drum, supported, and fitting freely, in the back head, and extending forwardly therefrom into the barrel; water tubes forming the sides of the fire and combustion chamber; a hollow mud ring, communicating with the water tubes of the fire chamber; a tube sheet secured to the barrel and closing the rear of the steam space thereof; a feed water communication, leading from the barrel to the mud ring and communicating with the combustion chamber water tubes; and a wrapper sheet, secured to the barrel and to the fire box, and performing the functions of rigidly connecting said members together, and forming a housing covering the roof of the fire box.

60 2. In a locomotive boiler, the combination

of a barrel; a fire box, comprising a combustion chamber and a fire chamber; a back head, having a rigid outer sheet and closing the rear of the fire chamber; a drum, supported, and fitting freely, in the back head, 70 and extending forwardly therefrom into the barrel; water tubes forming the sides of the fire and combustion chambers; a hollow mud ring, communicating with the water tubes of the fire chamber; a water cooled 75 bridge wall, mounted on the mud ring and secured rigidly only thereto, and extending across the fire box, and a wrapper sheet, secured to the barrel and to the fire box, and performing the functions of rigidly connecting said members together, and forming a housing covering the roof of the fire box.

3. In a locomotive boiler, the combination of a barrel; a fire box of side water tube construction, comprising a fire chamber and a combustion chamber; an upper drum, into which the water tubes of the fire box lead, said drum having a supporting engagement with the fire box and being free to move relatively thereto in expansion and contraction; 90 and a wrapper sheet, secured to the barrel and to the fire box, and performing the function of rigidly connecting said members together, and forming a housing covering the roof of the fire box.

4. In a locomotive boiler, the combination of a barrel; a fire box of side water tube construction, comprising a fire chamber and a combustion chamber; a drum extending horizontally through the tops of said chambers, 100 said drum being free to move relatively thereto in expansion and contraction; a common feed water connection, leading from the barrel to the side water tubes of the fire box and combustion chamber; and a wrapper sheet, secured to the barrel and to the fire box, and performing the function of rigidly connecting said members together, and forming a housing covering the roof of 105 the fire box.

5. In a locomotive boiler, the combination of a barrel; a fire box of side water tube construction, comprising a fire chamber and a combustion chamber; a hollow mud ring, secured to the fire box; a hollow bridge wall, 115 interposed between the fire and combustion chambers and rigidly secured to the mud ring only; and means for feeding water from the barrel to the bridge wall and the side water tubes.

6. In a locomotive boiler, the combination of a barrel; a fire box of side water tube construction, comprising a fire chamber and a combustion chamber composed of upper and lower cylindrical drums connected by side water tubes; a drum, supported, and fitting freely, in the back head of the fire chamber; and a wrapper sheet, secured to the barrel and to the fire box, and performing the function of rigidly connecting said members to 120

gether, and forming a housing covering the roof of the fire box.

7. In a locomotive boiler, the combination of a barrel; a fire box of side water tube construction, comprising a fire chamber and a combustion chamber; a rear tube sheet, depending below the bottom of the barrel; a water connection from the barrel to the walls of the fire box, supported by a downward extension of the rear tube sheet; and a wrapper sheet, secured to the barrel and to the fire box, and performing the function of rigidly connecting said members together, and forming a housing covering the roof of the fire box.

8. In a locomotive boiler, the combination

of a barrel; a fire box of side water tube construction, comprising a fire chamber and a combustion chamber; a rear tube sheet, depending below the bottom of the barrel; a water connection from the barrel to the walls of the fire box, supported by a downward extension of the rear tube sheet, a cover, closing a manhole in said connection and permitting access thereto; and a wrapper sheet, secured to the barrel and to the fire box, and performing the function of rigidly connecting said members together, and forming a housing covering the roof of the fire box.

ALFRED W. BRUCE.
